ATTORNEYS.

UNITED STATES PATENT OFFICE

WALTER C. GROSSEK, OF CLEVELAND, OHIO, ASSIGNOR TO THE DRAPER MANUFACTURING COMPANY, OF CLEVELAND, OHIO, A CORPORATION OF OHIO

PERFORABLE BUNG RING STRUCTURE

Application filed July 6, 1931. Serial No. 548,987.

The invention relates to closures for the bung openings of metallic barrels, drums, vessels, packages or containers utilized for shipping and/or storing liquid or semi-solid materials, and more particularly to the provision of means for completely draining the contents of a container having an internally projecting bung ring equipped with a "dual" seal as shown in my application for patent for container closure seals, filed April 20, 1931, Serial No. 531,292, upon which the present invention is an improvement.

Liquid or semi-solid materials are universally shipped in containers which also act as storage vessels for the materials. Accordingly, it is frequently desirable if not necessary to provide a "dual" seal in container closure construction including a sealing closure member seated by the usual plug in a container bung ring to prevent undetectable access to and removal of the contents of such containers and to provide a liquid seal for said theft indicating closure member, to prevent leakage between the bung ring and theft indicating closure member, as set forth in said application, Serial No. 531,292.

However, the provision of such a "dual" seal in container closure construction may require the bung ring to project a substantial distance into the container, which may prevent the contents of the container from being completely drained when the container is turned upside down for being emptied, because in such a position the bung ring projects upward into the container and a small quantity of the contents of the container remains below the level of the annular edge of the inner end of the bung ring.

A container bung ring has commonly been provided with apertures in the corner between its flange seamed to the container wall and its threaded ring portion, for permitting the remaining moiety of the container contents to drain out through the apertures when the container is turned upside down for being emptied.

However, such apertured bung ring construction cannot be used in connection with a "dual" seal closure because the apertures would permit egress of the contents of the

container therethrough beyond the "dual" seal, thus defeating the purpose of the "dual" seal and rendering the same useless and superfluous.

It is therefore an object of the present invention to provide a container having a "dual" sealed bung ring projecting a substantial distance therein with means for permitting the container contents to be completely drained. This may be accomplished by forming the container bung ring with one or more perforable thin-walled zones at the corner between its flange seamed to the container wall and its threaded ring portion. These thin-walled zones may then be readily perforated or punctured by the person emptying the container to completely drain the contents therefrom.

Moreover, it is a further object of the present invention to provide a simple, inexpensive and convenient method for making bung rings with perforable thin-walled zones by forming a perforated disk blank, drilling one or more holes partially through the blank so as to leave a thin wall at the bottom of the hole and drawing the blank to form a ring portion and an annular flange portion, and locating the axes of the drilled holes in a circumferential line substantially coinciding with the corner between the ring and flange portions.

These and other objects may be attained by the methods, combinations and structures, preferred embodiments of which are herein-after described in detail, and shown in the drawing, in which

Figure 1 is a plan view of a perforated disk bung ring blank in which two holes for forming thin-walled zones therein have been drilled partially through the blank;

Fig. 2 is an axial section through the bung ring blank on the line 2-2, Fig. 1;

Fig. 3 is an enlarged view of a portion of Fig. 2;

Fig. 4 is an axial section through a bung ring formed by drawing, threading and machining the blank shown in Fig. 1;

Fig. 5 is an axial section through a "dual" sealing cap or closure member;

Fig. 6 is a section through a container wall

to which the bung ring shown in Fig. 4 is seamed, showing the sealing member of Fig. 5 assembled therein and a closure plug about to be threaded therein;

6 Fig. 7 is an enlarged view of a portion of Fig. 6;

Fig. 8 is a view similar to Fig. 6, but showing the plug threaded into the bung ring locking the sealing member in "dual" sealing relation in the bung ring;

10 Fig. 9 is an enlarged view of a portion of Fig. 8;

15 Fig. 10 is a section through a container wall, showing a way in which the thin-walled zone of the bung ring may be perforated or punctured with a pointed tool after removing the plug and sealing member;

20 Fig. 11 is an enlarged view of a portion of Fig. 10;

25 Fig. 12 is a section through a fragmentary portion of a container turned upside down for completely draining the contents of the same through the perforated thin-walled zones; and

30 Fig. 13 is an enlarged view similar to Fig. 7 showing an alternate manner of providing a container bung ring with thin-walled zones.

Similar numerals refer to similar parts throughout the various figures of the drawing.

The improved perforable bung ring structure is preferably made from a disk blank 15 (Fig. 1) provided in the usual manner with a central aperture 16. One or more holes 17 are preferably drilled in the disk blank 15 partially through the same in such a manner that a thin wall 18 integral with the body of the disk blank remains at the bottom of the holes 17. When the holes 17 are formed by drilling, the thin walls 18 at the bottom of the holes will be slightly concaved downward somewhat as well shown at 18' in Fig. 3.

45 The disk blank 15 is then placed in a press and drawn to form a bung ring generally indicated at 19 having a ring portion 20 terminating at one end in an inwardly projecting annular flange 21, and at the other end in an outwardly projecting annular seam flange 22 from which a substantially cylindrical seam clamping portion 23 projects. The ring portion 20 is then internally threaded at 24 and the outer cylindrical surface of the clamping portion 23 is machined at 23' 50 so as to reduce the thickness of the same for readily seaming the bung ring to a container wall.

55 The bung ring 19 is then seamed to a container wall 25, at 26, by clamping the portions 22 and 23 to the annular curled edge 27 of a bung opening formed in the container 25, as shown in Fig. 6.

60 A bung opening closure plug is indicated at 28 and includes an exteriorly threaded portion 29, a flange 30, preferably shaped to re-

ceive a wrench, and a wrench receiving socket 31, the lower end of the threaded portion 29 being bevelled, tapered or chamfered as indicated at 32.

65 A cup-shaped metallic sealing element generally indicated at 33 (Fig. 5) which includes a disk bottom 34 and a circumferential rim flange 35 provided with an annular shoulder 36 provides the "dual" seal for the bung opening. A layer of sealing gum, or a sealing gasket formed of fibre, rubber or other liquid sealing material, indicated at 37 is preferably fixed, glued, cemented or otherwise attached to the outer surface of the sealing element rim flange 35 and shoulder 36.

70 In assembling the closure parts, the element 33 is first inserted into the bung ring opening so that the shoulder 36 thereof, faced by the liquid sealing material 37 rests on the bung flange 21 (Figs. 6 and 7). The closure plug 28 is then threaded into the threaded bung ring until the bevelled end 32 of the plug engages the upper annular edge of the cup rim 35. As the plug continues to be threaded into the bung ring, the rim 35 is placed under axial compression so that the cup-shaped sealing element is pressed downward and is self-locked to and seated against the bung flange 21, and the liquid sealing material 37 is squeezed in liquid tight sealing relation between the shoulder 36 and bung flange 21 (Figs. 8 and 9).

75 Moreover, the plug threads 29, cooperating with the bung threads 24, (Figs. 8 and 9) form threads 38 in the liquid sealing element rim flange 35, which are pressed or seated against the bung ring threads 24 adjacent the flange 21 thereof. Moreover, the liquid sealing material 37 is squeezed in liquid tight sealing relation between the threads 38 and bung ring threads 24, and the threads 38 maintain the rim 35 under compression so that the element 33 is in liquid tight sealing relation within the bung opening, and the disk bottom 34 thereof forms a theft indicating seal for the bung opening, it being necessary to puncture the disk bottom 34 in order to gain access to the contents of the container. The sealing element 33 thus provides a "dual" seal for the bung opening.

80 Although a container provided with a seated sealing element 33, and with the plug 28 removed, will withstand a pressure of at least ten pounds per square inch from within the container without leaking between the sealing element and the bung ring, yet in most cases the plug 28 remains during shipment and storage within the bung opening and sufficient clearance is provided between the lower end of the plug and the upper surface 85 of the disk bottom 34 so that the usual closure gasket 39 is clamped in liquid tight sealing relation between the plug flange 30 and the container wall 25.

85 The holes 17 are so located in the disk 130

blank 15 so that in forming the bung ring 19, the axes A of the holes 17 are located in a circle indicated by dot-dash lines in Fig. 1 at B, which substantially coincides with the 5 corner 40 formed between the ring and flange portions 20 and 22 respectively of the bung ring.

Accordingly, when the bung ring 19 is formed, the originally cylindrical holes 17 10 are distorted so that perforable thin-walled zones 41 result near the outer end of the completed bung ring adjacent the corner 40 thereof above the sealing element 33 and intermediate the bung ring flanges 21 and 22.

15 When it is desired to gain access to the contents of the container, the plug 19 is removed, and the sealing element 33 is punctured by a suitable tool and removed from the bung 20 opening, whereupon the contents of the container may be drawn off through the bung opening. At this time the thin-walled zones 25 41 may be readily perforated, pierced or punctured at 41a by any suitable pointed tool, as by a nail indicated in dot-dash lines in Fig. 10, so that when the container is turned upside down as shown in Fig. 12, the entire 30 container contents may be drained out through the punctured apertures 41a excepting only an insignificant amount indicated at 42, the level of which is shown in Fig. 12.

A slightly modified form of the invention is shown in Fig. 13 in which the holes 17a originally drilled in the disk blank for forming the bung ring 19a are drilled entirely 35 through the disk blank. After the bung ring 19a is completely formed, threaded and machined, the inner ends of the holes 17a are closed and sealed with soft solder indicated at 41b to provide readily perforable thin- 40 walled zones therefor.

Accordingly, the present improvements provide a closure construction which will give 45 a visible signal that someone has attempted to gain access to the contents of the container if the container is received by an authorized person and discloses any distortion or puncturing of the sealing element 33 or of the thin-walled zones 41, because it is necessary to puncture the same in order to gain access 50 to the contents of the container. However, the sealing element 33 and thin-walled zones 41 may be readily, quickly and easily punctured by any authorized person in order to gain access to the contents of the container 55 and to completely empty the container when desired.

Moreover, after the container has once been used it still has a salvage value and it may be filled and refilled time after time and 60 closed by the plug 28 seated in liquid tight sealing relation in the usual manner by the usual sealing gasket 39.

I claim:—

1. In closure construction for a container 65 having a wall, a bung ring projecting from

said wall, a theft indicating closure member locked in liquid tight sealing relation within said bung ring, and a perforable thin-walled zone in said bung ring above the closure member and adjacent to said wall. 70

2. In container closure construction, a threaded bung ring, a theft indicating closure member locked in liquid tight sealing relation to said bung ring threads at the inner end of the bung ring, and a perforable thin-walled 75 zone in said bung ring near the outer end thereof above the closure member.

3. In container closure construction, a bung ring having a ring portion and a seam flange portion with a corner formed therebetween, a theft indicating closure member locked in liquid tight sealing relation within the bung ring, and a perforable thin-walled zone adjacent said ring corner. 80

4. In closure construction for a container 85 having a wall, a bung ring projecting from said wall, a theft indicating closure member locked in liquid tight sealing relation within the bung ring, a plug for the bung ring, a sealing gasket between said plug and 90 ring, and a perforable thin-walled zone in said bung ring intermediate said sealing member and sealing gasket and adjacent to said wall. 95

5. In closure construction for a container having a wall, a bung ring provided with an inwardly projecting flange and an outwardly projecting flange, a theft indicating closure member locked in liquid tight sealing relation against said inwardly projecting flange, 100 said outwardly projecting flange being secured to said container wall, and a perforable thin-walled zone in said bung ring intermediate said flanges and adjacent to said wall. 105

In testimony that I claim the above, I have hereunto subscribed my name.

WALTER C. GROSSER.
